(57) **CLAIM**

The ornamental design for a bumper cover and protector, as shown and described.

DESCRIPTION

FIG. 1 is a perspective view of a bumper cover and protector draped over a bumper of a vehicle;

FIG. 2 is a perspective front view of the bumper cover and protector;

FIG. 3 is a front elevation view of the bumper cover and protector;

FIG. 4 is a rear elevation view of the bumper cover and protector, wherein the rectangular filled surface pattern near the top edge is representational of a textile with a hook fabric material for use with an environmental hook-and-loop fastener fabric;

FIG. 5 is a right elevation view of the bumper cover and protector, wherein the left side elevation view is a mirror image thereof;

FIG. 6 is a top plan view of the bumper cover and protector; and,

FIG. 7 is a bottom plan view of the bumper cover and protector.

The broken lines in FIG. 1 showing portions of an automobile are included for the purpose of illustrating environmental structure. All other broken lines shown in the drawings illustrate stitched lines for portions of the bumper cover and protector. All the broken lines in the drawings form no part of claimed design.
